No. 36,998.

Patented June 21, 1904.

UNITED STATES PATENT OFFICE.

ISAAC E. PALMER, OF MIDDLETOWN, CONNECTICUT.

DESIGN FOR A HAMMOCK.

SPECIFICATION forming part of Design No. 36,998, dated June 21, 1904.

Application filed May 18, 1904. Serial No. 208,613. Term of patent 14 years.

To all whom it may concern:

Be it known that I, ISAAC E. PALMER, a citizen of the United States, and a resident of Middletown, in the county of Middlesex and State 5 of Connecticut, have invented a new, original, and ornamental Design for a Hammock, of which the following is a specification.

The accompanying drawing illustrates a section of hammock embodying my new, original, and ornamental design, such illustration rendering the same clear without further description.

What I claim is—

The ornamental design for a hammock substantially as herein illustrated.

ISAAC E. PALMER.
